ANTISPLASH SHIELD

Clarence F. Norlin, Chicago, Ill.

Application July 9, 1943, Serial No. 493,996

4 Claims. (Cl. 36—70)

This invention relates to footwear and particularly to an anti-splash device for the heels of the footwear to prevent the discharge of dirty water from the heel cap onto stockings or trousers.

The present invention is an improvement on my splash shield Patent No. 2,292,466, issued August 11, 1942. In this patent, I fully describe the problems involved which will not be repeated herein. Reference may be had to this patent for such details.

My experience with splash shields has disclosed that some users are opposed to wearing flappy splash shields and therefore I experimented to develop smaller, firmer anti-splash devices.

The particular object of this invention is to provide a small comparatively rigid device or structure which will prevent the drops of dirty water from being thrown by the heel cap.

Other objects and benefits will be disclosed in the following descriptions and drawing in which:

Fig. 1 is a side elevation view of a lady's shoe equipped with my anti-splash device;

Fig. 2 is a back elevation view of the shoe shown in Fig. 1;

Figs. 3, 4 and 5 are enlarged side elevation views showing the operation of my anti-splash device as will later be explained;

Figs. 6, 7, 8 and 8a are enlarged perspective views of optional structures which will be discussed and explained;

Figs. 9 and 10 are enlarged broken side elevation views of storm rubbers equipped with my anti-splash devices formed integrally therewith.

Now referring to Figs. 3, 4 and 5 I show how water adheres to the heel cap when the wearer steps in water as in Fig. 3, how droplets adhere to the heel cap when the heel is lifted as in Fig. 4 and how these droplets run together at the back of the heel cap when the wearer's foot reverses its upward sweep and starts downwardly as in Fig. 5. The curved back of the heel tends to run the droplets together in large drops at the back of the heel cap where these drops attain sufficient size and weight to be impelled upwardly by the sharp foot movement thereby to cause soiling of the limb clothing.

I have found that a small shield slightly removed from the heel cap—a sufficient distance to permit the drop to form on the rear edge of the heel cap (about $\frac{1}{4}$ inch) will stop and break up the drops dissipating their inertia to thus prevent them being thrown upwardly. This small narrow edged shield is not of sufficient size

to permit large drops to be formed thereon and is not of itself a splashing hazard, because it is the flat normally horizontal bottom surfaces which gather the large drops.

Now referring to Fig. 6, I show a preferred form of my invention in which a small shield 19 is attached to a resilient rubber band 18. This shield may be attached to a heel 16 of a shoe 15 as shown in Figs. 1 and 2. This shield 19 being of rather sturdy structure is quite firm and may be used as a tab in applying the band 18 over the heel 16. I advise placing the end of the shield 19 at the level of or slightly below the heel cap 17 where it is positioned slightly away from the rear end of the heel cap as shown.

The entire device being rather small and firmly positioned low on the heel is inconspicuous. In action the shield has practically no relative movement with the heel and merely acts as a fixed shield as heretofore explained.

In the preferred embodiment as described, the device is integrally formed from rubber.

Now referring to Fig. 7 I show an optional form of shield wherein the attachment member 20 is made from spring steel with a fixed shield 21 attached thereto. In this form, the device is fixed in position by forcing the open end of the spring 20 over the rounded rear end of the heel and into firm resilient contact with the heel, with the shield 21 in the slightly removed position with respect to the heel cap,—the same as the shield 19 in the form shown in Fig. 6. It will be appreciated that a similar structure may be made from phenolic condensation or plastic materials to give the same results.

In Fig. 8, I show an optional structure utilizing a round spring wire member 22 having a shield 23 mounted thereon. This structure may be modified by mounting a pivotal shield member 24 on the spring wire 22 and providing an integral stop section 24s thereon to stop the shield in the proper slightly removed position from the heel cap.

In Fig. 9 I show a fixed shield member 26 affixed to the heel 25 of a conventional storm rubber. This structure may be modified as shown in Fig. 10 wherein an upwardly projecting slot 28 is formed in the heel. In this arrangement, I may provide a rearwardly projecting opening 29 at the top of the slot 28 to prevent clogging of the slot and a pair of side openings 30 above the bead of the heel cap connecting into the slot 28 to catch drops of water on top of the heel cap bead.

In all the options I illustrate structures adapted

to utilize a common principle of operation, namely, a small comparatively inflexible shield positioned slightly to the rear of the heel cap in order to permit drops of water to form at the rear of the heel cap with the shield immediately adjacent the drops of water in position to stop and break up these large drops from being discharged from the heel cap, by immediately dissipating their inertia, thus to prevent their discharge upwardly to soil limb clothing.

I appreciate that the structures shown may be further modified and I do not desire to be limited to these specific structures except as such limitations are imposed by the claims.

I claim:

1. In an antisplash device for footwear, a small vertical relatively rigid splash shield having a thin bottom edge mounted closely adjacent the heel cap of the footwear, to permit large drops of water to form on the rear of the heel cap and then to prevent the water drops from being discharged upwardly from the heel cap onto limb clothing.

2. In an antisplash device for footwear, a small vertical relatively rigid splash shield having a thin bottom edge to cover the rear of the heel cap and flexible fastening means to attach the shield to the heel of the footwear at a position slightly removed from the rear edge of the heel

cap to permit large drops of water to form on the rear of the heel cap and then to prevent the water drops from being discharged upwardly from the heel cap onto limb clothing.

5 3. In an antisplash device for footwear, a small normally inflexible vertical relatively rigid splash shield having a thin bottom edge to cover the rear of the heel cap and flexible fastening means to attach the shield to the heel of the footwear

10 10 at a position slightly removed from the rear edge of the heel cap to permit large drops of water to form on the rear of the heel cap and then to prevent the water drops from being discharged upwardly from the heel cap onto limb clothing.

15 4. In an anti-splash device for footwear, a small inflexible splash shield having a thin bottom edge to cover only the rear rounded section of the heel cap, said width being considerably narrower than the width of the heel, and flexible

20 20 fastening means to attach the shield to the heel of the footwear at a position only slightly removed from the rear edge of the heel cap, said fastening means being so narrow and thin as to avoid changing the lines of the heel, the general proportions and arrangement of the device being 25 so small and generally inconspicuous as to avoid changing the general appearance of the footwear.

CLARENCE F. NORLIN.
